VALVE MECHANISM

Glenn T. Randol, Mountain Lake Park, Md.

Application June 7, 1957, Serial No. 664,431

12 Claims. (Cl. 121—46.5)

The present invention relates to improved novel valve mechanism designed for controlling a fluid circuit, said invention constituting an improvement related to the switch mechanism disclosed in U.S. Patent No. 2,716,678 granted to me August 30, 1955.

Broadly, this invention concerns a valve mechanism for selectively opening or closing a fluid circuit adapted to control the operation of a fluid pressure energizable apparatus or the like, the latter may be situated either approximately or remotely relatively to said mechanism.

More specifically, my invention is directed to the provision of new and novel valve mechanism operable in response to minute reciprocatory movements of an element which may be frictionally actuated, for example, by an automotive accelerator pedal, by a servomotor piston, by mechanical linkage, or by manual- or speed-responsive means; said element being adapted to control, in a novel manner, movement of a compound assembly comprising a pair of engaging elements relatively movable with respect to each other and to a fixed element for effecting open and closed conditions of the mechanism.

Preferably, but not necessarily, the valve mechanism comprising the present invention is pivotally mounted, so as to compensate readily for corresponding movements of a reciprocatable or oscillatable actuating element, as will appear.

The primary objects of my invention therefore, are the provision of a compact and simple valve mechanism responsive to minute reciprocative movements of a frictionally connected actuating element, for selectively closing and opening a fluid circuit at any point along the full operating stroke of said element; the provision of means for suitably mounting said valve mechanism on a support to accommodate actuation thereof; the provision of means incorporated in said mechanism for accommodating minute movements of the actuating element without affecting the then existent relative disposition of the circuit controlling elements; and the provision of means for normally maintaining the valve mechanism in circuit-open position.

A further and important object of the invention related to the series of primary objects immediately preceding, is the provision of valve means to accommodate a full operating stroke of the actuatable element relative to either an open, or a closed position of an included movable element assembly, and wherein said movable assembly is operable to open and closed positions substantially at all points along the full stroke of the actuatable element responsive to minute reciprocative movements of said element within its operating stroke aforesaid, thus to produce in effect, a follow-up control of the energization and de-energization of a device such as, for example, a fluid pressure-operated servomotor controlled by said means.

Another object relative to that immediately preceding, is the provision of novel means to enable continued movement of the actuatable element in one direction

2

after the movable assembly has been moved to closed position, without affecting the closed disposition of the assembly; to enable continued movement of the actuatable element in the opposite direction after the movable assembly has been moved to open position, without affecting the open disposition of the assembly; and to enable arrested movements of the actuatable element during the full operating stroke thereof in either direction, without affecting the then obtaining disposition of said assembly.

A further and more specific object related to the two immediately preceding objects, resides in the utilization of an automotive vehicle engine accelerator mechanism as the personal responsive means for operating the actuatable element of the valve mechanism, the latter including means for accommodating the full stroke of the accelerator throughout its engine controlling range of movement, and adapted responsive to minute reciprocations of said accelerator transmitted to said actuatable element, to operate the valve mechanism for opening and closing the fluid pressure circuit of a power device, whereby to control the operation thereof and thus provide in effect, a follow-up control therefor.

The present invention also contemplates novel utilization of a single movable element in lieu of the compound assembly aforesaid for establishing the open and shut conditions of the valve mechanism.

In the more comprehensive and detailed description to follow, features and advantages not specifically recited hereinbefore will be apparent or noted, reference being had also to the accompanying drawing in which the preferred embodiments of my invention are illustrated as described below:

Figure 1 is a diagrammatic layout of a servomotor control system wherein is incorporated the valve mechanism comprising the present invention;

Figure 2 is a longitudinal section on an enlarged scale of the valve mechanism per se shown in Figure 1;

Figure 3 is a vertical sectional view taken along the line 3—3 of Figure 2;

Figure 4 is a further enlarged reproduction of the major portion of Figure 2, the valve being shown in closed position; and

Figure 5 illustrates a modified form of the invention wherein the movable valve assembly comprises a single element shown in open position.

Like characters of reference designate like parts in the several views with like parts in the Figure 5 modification distinguished, however, by the addition of the letter "a" to each numeral and the exponent "1" to each letter.

The valve mechanism comprising the instant invention is designated in its entirety by the letters "VM," and its incorporation in a vacuum-actuated servomotor controlled system, generally designated "SMC," has been resorted to for illustrating and explaining the new and novel construction and operation thereof.

The illustrated valve actuating element of said system comprises, by way of example, a rod 24 reciprocatable by means of a pedal such as an engine accelerator 26 for an automotive vehicle, in conjunction with a normally preloaded expansion spring 28 for opposing foot operation thereof, as should be apparent from an inspection of an exemplary installation shown in Figure 1.

It is here noted that the rod 24 typifies any similar reciprocating element characterized by axial or rotational movement, either mechanically or manually actuatable to effect the operation of the valve mechanism VM in a new and novel manner to be described.

The valve mechanism VM as seen to best advantage in Figures 1, 2, and 3, includes a cup-shaped casing generally designated "C"; a movable valve assembly generally

designated "MA"; a fixed valve assembly generally designated "FA"; and a support for the mechanism generally designated "S".

The cup-shaped casing C includes a cylindrical body portion 30; an end wall 32; an externally projecting reduced tubular portion 34 integral with the latter and terminating in an inturned right angle flange 35 formed with a coaxial right angle outturned bearing collar 36; a plurality of atmospheric ports 37 circumferentially disposed through the flange; an angular embossment 38 extruded outwardly from the end wall between the body and tubular portions; a cup-shaped fitting 39 attached exteriorly to said embossment; a passageway 40 through the end wall of the fitting communicating with the interior of the casing; another cup-shaped fitting 41 secured to the exterior of the cylindrical portion of the casing medially thereof; a passageway 42 through the end wall of the latter fitting establishing communication with the interior of the casing; and a plurality of holes 43 equally spaced circumferentially adjacent the open end of the cylindrical portion of the casing.

The movable assembly MA includes a pair of telescopically related relatively movable poppet-type valve elements 44, 45, the outer element 44 comprising a tubular extension 46 having a longitudinal bore 47 therethrough and a plurality of coextensive longitudinal atmospheric channels 48 communicating with an internal annular space 49 at the inner end formed in the cylindrical surface of the bore 47; an annular external flange head 50 terminating the inner end of extension 46; inner and outer concentric angular ring seats 52, 53 formed in the end surface of the flange 50. The inner element 45 comprises: an inner terminating tubular body portion 55 having a longitudinal bore 56 and a tubular reduced diameter extension 58 projecting from the other end through the bore 47 and having a correspondingly reduced longitudinal bore 59 coaxially disposed with respect to the bore 56 and collar 36; an internal annular shoulder 60 at the point of merger of the bores 56, 59; and an angular ring-type seat 62 defining an external annular shoulder between the exterior surfaces of the tubular portion 55 and extension 58; an external annular channel 64 provided in the exterior cylindrical surface of the extension 58 adjacent the end thereof and normally spaced from the end of the extension 46; a split-type retainer ring 65 engaging said channel; a helically formed normally preloaded compression spring 66 encircles the portion of the extension 58 projecting beyond the extension 46 with the opposite ends thereof reacting on the end of the extension 46 and retainer ring 65 to bias the inner and outer elements away from each other to intimately engage the concentric valve seats 52, 62 in air-tight sealed relationship best demonstrated in Figure 2; an annular fluid chamber 68 in continuous communication with passageway 40 and disposed between the end wall 32 and confronting face of the valve flange 50; an annular atmospheric chamber 69 provided between the end of the extension 58, flange 35, cylindrical wall of the tubular casing extension 34 and spring encircled portion of the extension 58 and having continuous communication with the atmosphere via ports 37 and a cup-shaped breather or venting cap 70 press-fitted on the horizontal collar 36 with the end wall 71 spaced slightly from the flange 35 and the cylindrical wall 72 overlying a portion of the end of the extension 34 in spaced relationship with respect to the latter, said cap acting as a baffle to filter out foreign particles from entering the chamber 69 and also silence the ingress of air through the ports 37; the actuating cylindrical rod 24 has a normal diameter portion 75 which operably projects through the collar 36, the latter acting as a bearing support therefor, and the bores 56, 59 and terminates at its free end into an enlarged diameter portion 76 having a pair of longitudinally spaced V-grooves 77, 78 in its cylindrical surface and which defines an external annular shoulder 79

with the normal diameter thereof for an important functional purpose as will later appear; a cylindrical bushing 80 formed at its outer end normally adjacent said shoulder 79 with an internal annular flange 81, said bushing being of the same length as the bore 56 and press-fitted therein for movement with the inner valve element 45, and is provided with an internal annular channel 82 between the flange 81 and internal shoulder 60 for reception of a contractible friction sleeve 83 longitudinally split at 84 for continuous frictional engagement around the rod 24 whereby the frictional coefficient normally obtaining between the sleeve 83 and rod portion 75 is of such magnitude as to impart like limited movement to the inner valve element 45 as will appear.

The fixed assembly FA comprises a cylindrical body portion 85 with an external diameter of substantially the same internal diameter as the cylindrical portion of the casing C to accommodate telescopic assembly thereof to produce the valve mechanism VM; an external flange 86 terminates the outer end of the cylindrical portion 85 and forms therewith an external annular shoulder 87 engaged by the open end of the casing C; a corresponding number of circumferentially equally spaced threaded holes 88 are provided in the cylindrical portion 85 adjacent the shoulder 87 for receiving in threaded engagement, for example, cap screws 89 which project through the holes 43 in the casing cylindrical wall whereby the casing C and assembly FA are secured in a unitary assembly; the outer end of the portion 85 is coaxially provided with an annular embossment 90 with an offset smaller embossment 91 for the outer terminus of the portion 85; a longitudinal bore 93 extends from the outer terminus of the body portion 85 to merge with a counterbore 94 in which the tubular portion 55 of the inner valve element 45 is slidably mounted, said point of merger defining an internal annular shoulder 95 intermediate the extremes of said body portion to serve as a stop to limit the leftward movement of the movable assembly MA, and the opposite end of the extension 58 normally engages the confronting marginal face portion of the flange 35, as shown in Figure 2, to limit the rightward movement of the movable assembly MA. Accordingly, the inner face of the flange 35 and shoulder 95 define the limit of reciprocatory movement of the movable valve assembly MA for opening and closing the valve mechanism VM while the actuating rod 24 is provided with a predetermined operating stroke of greater length than the minute reciprocation of the movable assembly MA, in accordance, for example, with the operating range of movement of the pedal 26 whereby the frictional engagement between the inner valve element 45 and actuating rod 24 enables limited reciprocations of the movable assembly MA at selected points along the full operating stroke of the pedal 26 within the extremes thereof for novel purposes as will hereinafter appear.

The inner end of the valve body portion 85 is provided with an annular valve seat 98 in confronting relation with respect to the outer seat 53 on the outer valve element 44 and normally slightly spaced apart as depicted in Figure 2, said seat 98 merging at its inner marginal edge with an annular fluid chamber or space 101 in continuous communication with a plurality of longitudinal passageways 103 communicating with an annular internal passageway 104 provided in the surface of the counterbore 94 spaced to the left of chamber 101, the annular space 104 being connected to a plurality of radial passageways 106 connected to an external annular passageway 107 in circular alignment with the passageway 104, the latter annular passageway 107 having continuous communication with the fitting passageway 42, and preferably flexible fluid conduits 109, 110 connected respectively to the fittings 39, 41 as by short rigid tubes 112, 113 to convey the fluid actuating pressure to the apparatus to be controlled by the valve mechanism VM.

An internal annular groove 115 is provided in the longitudinal bore 93 adjacent the outer end thereof, said bore

being fitted with a split-type radially resilient ring 116 having, for example, one end formed with an inwardly extruded detent portion or ridge 117 for selective engagement in the actuator grooves 77, 78 whereby the movable valve assembly MA is releasably stabilized in its two operating positions as shown in Figures 2 and 3. The free end 76 of the actuating rod 24 is slidably supported by and projects through the bore 93 to the exterior of the body portion 85 in coaxial disposition with respect to the bearing collar 36 to maintain the parts of the valve mechanism in proper operating relationship.

The support S comprises a laterally extending boss 120 integral with the left end of the fixed valve portion 85 as shown in Figure 3. This boss is axially bored at 121 for the reception of a pivot pin 122 in press-fitted relation for oscillation therewith, the outer end of the pin having an annular external channel 123. A fixed support or mounting member 124 is provided with a coaxial bore 125 for reception of the outer end of the pin 122 for relative rotative movement with respect thereto, and a cross locking pin 126 is press-fitted through a cross bore 127 in alignment with said channel 123 to freely pass through the latter to prevent lateral displacement of the valve mechanism VM with respect to its support S yet accommodating such oscillatory movement thereof in accordance with the deflection of the actuating rod 24 from a path of straight line movement resulting from the arcuate sweep of the pedal 26 as is understood.

OPERATION

As hereinbefore noted, the valve mechanism VM of the present invention is illustrated in Figure 1, for explanatory purposes, as incorporated in a servomotor control system designated as a whole "SMC." Said system includes, in addition to the structure already enumerated: a vacuum tank "T"; an internal-combustion engine intake manifold "IM"; engine carburetor "EC" and associated throttle valve "TV"; a fluid control circuit "FC" for connecting the carburetor EC, tank T via a check-valve "CV," valve mechanism VM of the present invention, and servomotor SM in series; suitable linkage "L" for mechanically connecting the throttle plate TV with the pivotally mounted accelerator pedal 26 via multiple arm lever "ML" pivotally mounted on a bracket "BR" secured as by bolts to the engine compartment side of the vehicle firewall "FW"; and the expansion spring 28 anchored at one end to the firewall FW and the other end connected to a portion of the linkage for biasing the pedal toward released engine idling position depicted in the figure.

The pedal 26, carburetor EC, tank T, and the servomotor SM are of conventional design, therefore describing these components in structural detail is not believed necessary for a clear understanding of the operation of the control system SMC. However, for a better understanding of the subsequent description of operation, it is believed advisable to alphabetically designate the most pertinent elements.

Thus, the piston of the servomotor SM is designated *a*; its piston rod is designated *b*; a normally preloaded compression return spring is indicated *c*; a breather cap *d*; and a pivotal mounting for the unit SM is indicated at *e*.

The letter *s* designates a rotatably mounted shaft, the rotation of which in either direction is controlled by the movements of piston rod *b*, which is shown to have a pivotal connection *f* with a link *g*, the latter rigid with one end of said shaft. It is noted that the shaft *s* is typical of any similar element the rotation of which is responsive to the action of said system under the influence of the valve mechanism VM.

In other words, the shaft *s* may serve, for example, as the operating element of an automobile braking system, or as the control member for a friction clutch. Again, the shaft *s* may represent a rotatable member for raising and lowering a radio antenna, and so on. It is also noted that the pedal 26 is typical of any suitable means, either

mechanically or manually operable, for imparting reciprocatory motion to the rod 24.

It will be assumed that the shaft *s* constitutes the control for a conventional friction type clutch of an automotive vehicle. The illustrated servomotor system SMC exhibits the normal status of the included mechanical components when the engine of said vehicle is idling, and the valve device VM open as shown in Figure 1 with the closed position indicated as by the dashed line position of the pedal 26.

At such time, the valve VM is in open condition whereby the thus established vacuum factor obtaining between the tank T and servomotor SM maintains the piston *a* rearwardly against the forwardly biasing force of compression return spring *c*, as should be apparent. Consequently, assuming that the portrayed disposition of link *g* indicates a clutch-disengaged status, the status quo will continue to obtain so long as the rod 24 is not perceptibly, that is positively activated, in an engine accelerating direction.

In other words, and with particular reference to Figure 2, the shoulder 79 on the actuating rod 24 is in contact with the split friction sleeve flange 81 thus establishing the movable assembly MA in fully retracted position wherein the inner end of the valve extension 58 engages the confronting surface on the inner side of the casing flange 35 to establish said assembly in firm fluid circuit open condition. That is to say, the spring enclosing power chamber of the servomotor SM is evacuated of air to produce the pressure differential on opposite side of the piston *a* causing the piston to assume the position shown in Figure 1. This evacuating process to activate the servomotor is brought about through the instrumentality of the present valve device VM in the following manner.

With the parts in the positions shown in Figure 2, as a result of the biasing effect of spring 28 on the pedal 26 and connected linkage L, and the rod 24 correspondingly biased therewith, it will be noted that the valve seats 52, 62 are firmly engaging each other in air-tight sealing relationship, while the valve seat 53 is slightly separated from its mating seat 98 on the fixed body portion 85. Accordingly, the vacuum tank T being continuously in communication with valve chamber 68 via conduit 109 is connected via the separated valve seats 53, 98, annular space 101, passageways 103, annular passageway 104, radial passageways 106, annular passageway 107, thence through the passageway 42 in the fitting 41 to the conduit 110 and servomotor vacuum-power chamber to energize the latter as is understood. While the valve parts are in the positions explained above to energize the vacuum servomotor, it should be importantly noted that the biasing force of the spring 28 serves to urge the shoulder 79 on the actuating rod 24 into engagement with the bushing flange 81 carried by the inner valve element 45 thereby operating the movable valve assembly MA toward the right as viewed in Figure 2. This operation places the valve seats 52, 62 in intimate air-tight sealing relationship due to the counter force of the spring 66 and upon seating of the valves 44, 45 as aforesaid they move simultaneously under the influence of the spring 28 to the position of separating the seats 53, 98 as clearly portrayed in Figure 2 wherein the end of the valve extension 58 is in engagement with the inturned flange 35 of the casing C to limit the degree of space between the seats 53, 98. Also it should be noted that with the air controlling seats 52, 62 in engagement, the annular atmospheric space 49 is isolated from the fluid chamber 101 thereby establishing the valve mechanism in open condition.

Closure of the valve mechanism is accomplished by reversal of the operations noted above for opening it. Reference is now made to Figure 4 wherein the valve parts are shown in their respective positions for establishing closed condition thereof which isolates the vacuum

charged chamber 68 from communicating with the annular passageway 101 and places the atmosphere in communication therewith via the vents 37, chamber 69, channels 48, and annular space 49 whereby the servomotor power chamber is vented to atmosphere to equalize the pressure on opposite sides of the piston *a* enabling the return spring *c* to move the latter to its extreme right position to accommodate closure of the friction clutch members to engage the same for transferal of drive torque to the driving wheels of the vehicle. This closing operation is illustrated as initially effected at substantially the dashed line position of the accelerator pedal 26 in Figure 1, however, as the foregoing description considered with the drawings clearly made clear, the opening and closing of the present valve mechanism may be accomplished at a plurality of closely selected positions within the extremes of the full operating stroke of the actuating rod 24, and therefore, the associated automotive friction clutch may be disengaged and re-engaged at as many selective points along the full operating movement of the accelerator pedal 26 to simulate what may be termed a "follow-up" control for smoothly regulating the clutch friction members into smooth engagement. This follow-up operation provides the unique advantage of driver feel in controlling the engaging action of the clutch for smooth starting of the vehicle, in response to minute reciprocations of the accelerator pedal at any point along the full range of operating movement thereof to cause the clutch to lock and to withdraw so as to prevent stalling of the engine during the critical phase of starting the vehicle. Thus, if the driver fails to give the engine sufficient throttle for the load and road conditions involved, only slight release of the accelerator pedal 26 from whatever engine accelerating position effective will cause instant operation of the servomotor to disengage the clutch to prevent engine stall. If the engine should be operating at substantially one-third throttle and the degree of clutch engagement causes substantial reduction in the speed of the engine, all the driver must sense is to instinctively slightly relax his foot from the pedal 26 which results in the clutch disengaging and increase in engine speed followed by further depressing of the pedal from the then existing accelerating position to cause the clutch to re-engage and the vehicle smoothly underway with accelerating power as desired.

As soon as the valve device VM assumes its open position shown in Figure 2, the compression spring *c* biases the piston *a* forwardly, the servomotor being vented via breather cap *d*. Consequently, shaft *s* is rotated counterclockwise from its illustrated position, to effect engagement of the exemplary clutch. This clutch-engaged status will continue so long as the pedal 26 is sufficiently depressed to maintain the valve open as depicted in Figure 4.

That is to say, a slight release due to vehicular vibration and so on, will not disturb the clutch-engaged status quo, because of the frictional engagement of the sleeve 83 about the rod 24 aforesaid stabilized by engagement of detent 117 in groove 78. However, it is noted that the invention provides a novel and effective mechanism for intermittently opening and closing a fluid circuit with the pedal 26 in an approximately intermediate, or at substantially any position along its full operating stroke, to produce in effect, an operational result simulating a follow-up control of the associated power device illustrated as the servomotor SM.

Thus for example, reverting to Figure 2, it is seen that the split friction sleeve 83 has its bushing 80 engaged by shoulder 79 to establish the movable contact assembly MA in its fully open position. It will be remembered that Figure 4 is illustrative of a valve status which may obtain at any depressed stage of the pedal 26 intermediate its two extreme positions.

Consequently, assuming that said pedal 26 is now depressed slightly to the dashed line position thereof portrayed in Figure 1, the friction sleeve 83 will automatically carry the assembly MA to a closed position, with the valve element 44 engaging its seat 98 and the seats 52, 62 separated to place conduit 110 and consequently the servomotor power chamber in communication with the atmosphere. Also note that the inner end of the inner valve element 45 engages the stop shoulder 95.

Assuming now that the pedal is again released slightly, the sleeve 83 will carry the valve elements 44, 45 therewith to reopen the valve VM. Thus it should be manifest that rapid intermittent openings and closings of the fluid circuit may be effected at any intermediate position of the pedal by the alternate release and depression thereof, irrespective of the then obtaining disposition of the movable valve assembly MA. It should further be manifest that complete release of pedal 26 from any intermediate depressed position thereof, will automatically cause the valve mechanism to revert to its Figure 2 disposition.

Whenever said pedal is in its normal position, the right end of friction sleeve carrier 45 as viewed in Figure 2, is engaged against the casing flange 35. It is noted however, that the spring detent 117 and cooperating groove 77 serve to assist in maintaining the open status of the valve elements 44, 45 and also act as a stabilizing influence thereon so that a positive and deliberate depressing movement of the pedal 26 is required to close the valve at any selected point along the full operating stroke of the pedal.

That is to say, a slight depression of pedal 26, short of the suggested broken line position appearing immediately adjacent the full line position thereof, will not affect the existent fluid circuit-opening relation of the valve members 44, 45, because during the concurrent slight movement of the pedal away from its fully released position under influence of the spring 28, a degree of lost-motion normally existent in the linkage due to wear and other factors must be first taken up before the actuating rod 24 moves simultaneously with pedal movements.

Therefore, it is only when the pedal 26 is positively depressed, for example from the said full line position to the second suggested broken line position thereof, that the fully closed position of the valve mechanism demonstrated in Figure 4 is had.

In this connection, it should be noted that the frictional coefficient obtaining between spring sleeve 83 and rod portion 75 is of such magnitude as to overcome the selective engagement of the detent 117 with its cooperating grooves 77, 78, but if the rod 24 is given a stroke greater than required to place the valve VM in its two operating positions (open and closed) as defined by the spacing of the grooves 77, 78, after the detent 117 has engaged the groove 78 as by further depressing the pedal 26 beyond its dashed line position shown in Figure 1 in an engine accelerating direction, the detent 117 would automatically disengage from groove 78 and ride the cylindrical portion 76 of the actuator rod 24 to accommodate the full operating movement of the pedal 26 from engine idling position to full engine accelerating position as is understood.

Consequently, as the pedal 26 is being positively depressed from the first to the intermediate broken line position thereof, the left end of valve element 45 engages against the shoulder 95, and thereupon said movable assembly remains in that position whereby slipping engagement of the friction sleeve 83 and release of the detent 117 from groove 78 accommodate further depressing movement of the actuating rod 24 in the same direction to the limit of its full operating stroke corresponding to wide open engine throttle.

Modified structure and operation

Figure 5 illustrates a modified form of the invention in which corresponding parts are designated by like characters of reference distinguished, however, by the addition of the letter "a" to each numeral and the exponent "1" to each letter, only the open position of the modified movable assembly MA¹ is shown, and it may be assumed that otherwise the components correspond to those of the embodiment first disclosed (Figures 1-4 incl.).

A modified fixed assembly FA¹ is substituted for the assembly FA and comprises a cylindrical body portion 130 forming a unitary assembly with the casing C¹ in the same manner as previously described with the open end of the casing wall engaging the annular shoulder 87a. The inner end of body portion 130 is provided with a projecting arcuate segment 131 terminating in an angular end face 132 having a circular recess 133. A sealing washer 134 engages the recess and in the assembled status of the casing C¹ and fixed assembly FA¹ the washer is brought into intimate contact under slight compression with the inner surface of the casing embossment 38a to form an air-tight seal therebetween whereby the passageway 40a in the end wall of the fitting 39a registers with a circular opening 135 through the washer to place the conduit 109a in continuous communication with an aligned longitudinal passageway 136 formed in the segment 131. A fluid chamber 137 is provided by the emergence of the chambers 68, 69 of the first embodiment due to elimination of the valve element 44. This chamber is vented to the atmosphere via ports 37a in the casing flange 35a. The longitudinal passageway 136 intersects a radially disposed passageway 138 in continuous communication with a cross channel 139 in the outer cylindrical surface of the body portion 130. A diametrically opposed radial passageway 140 is provided in the body portion in alignment with the radial passageway 138, and which opens into a cross channel 141 in the opposite surface of the body portion 130, the latter channel having continuous communication with the passageway 42a in the fitting 41a.

The modified movable assembly MA¹ comprises a single cylindrical tubular element 144 having a normal diameter portion 145 with the longitudinal bore 56a and a reduced diameter portion 146 longitudinally bored at 59a to merge coaxially with the bore 56a. The point of emergence between said bores defining the internal annular shoulder 60a in substantially circular alignment with the angular external shoulder 62a, the latter being formerly the ring valve seat 62 in the first embodiment, and the free end of the portion 146 normally engaging the inner marginal face of the flange 35a to limit the rightward movement of said element 144 wherein open condition of the valve mechanism VM¹ is established as portrayed in the figure. Formed in the exterior surface of the portion 145 medially thereof is an annular passageway 148 normally connecting the radial passageways 138, 140 whereby the conduits 109a, 110a are connected via washer opening 135, passageway 136, radial passageway 138, annular passageway 148, radial passageway 140, cross channel 141, and passageway 42a, to place the valve mechanism VM¹ in open condition when the pedal 26a is in its fully released position as shown in Figure 1. A valve land 150 projects from a lower side portion adjacent the annular passageway 148, and extending from the opposite side of said land is a longitudinal surface channel 151 opening into the chamber 137 thereby placing this channel in constant communication with the atmosphere via the openings 37a in the casing flange 35a and breather cap 70a. This valve land being operative for selectively placing the annular passageway 148 and channel 151 in communication with the radial passageway 140 to establish open and closed conditions respectively of the valve device VM¹. To maintain the slidable valve element 144 from relative rotative movement so that the channel 151 will

register with the radial passageway 140 for communicating therewith, a lug 153 is struck from the circular edge of the extreme end of the collar 36a, and which engages a longitudinal surface groove 154 in the actuating rod 24a to thus prevent rotative movement of the rod but 5 accommodating slidable movement thereof, and the reduced diameter portion 146 of the tubular valve element 144 is provided with a press-fitted pin 155 through the wall thereof into engagement with groove 154 to thus 10 prevent relative rotative movement between the element 144 and rod 24a. In this way the slidable element 144 is maintained in proper position so that when reciprocated responsive to like actuations of the rod 24a, the atmospheric channel 151 will connect the inner end of the radial passageway 140 to atmosphere in the closed position of the valve device VM¹.

The valve element portion 145 carries the press-fitted bushing 80a with the flange 81a to form the internal annular channel 82a with the internal shoulder 60a for 20 reception of the split contractible friction sleeve 83a in the same manner and for the same purpose as described in connection with the first embodiment Figures 1-4 inclusive. The shoulder 95a is engaged by the inner end of valve member portion 145 to limit the leftward movement of the slidable valve element 144 whereby the limit of reciprocative movement is defined by the opposite end of the extension 146 engaging the flange 35a to limit the rightward movement thereof.

In operation, this modified structure operates in the 30 same manner as already described in connection with the operation of the first embodiment responsive to minute reciprocations of the actuating rod 24a by the pedal 26a at substantially all points intermediate the extremes of the fully operating movement of said rod and pedal, to 35 open and close the valve VM¹. The split friction sleeve 83a moves the valve element 144 simultaneously with the rod 24a to the open position shown in Figure 5 wherein in the end of the extension 146 engages the flange 35a and the annular passageway 148 connects the radial passageways 138, 140 and in the opposite direction to place the atmospheric channel 151 in communication with the conduit 110a and to cut off communication between the radial passageways 138, 140 to establish the parts in closed disposition.

As will be appreciated this modified construction requires slightly longer reciprocative movements of the valve element 144 to connect and disconnect the conduit 110a with respect to the tank T¹ since such operating movement must include the added distance of the width of the valve land 150 required to place this land out of registry with the radial passageway 140 to open the valve as is understood, however, there is a simplification of the structure produced with attendant lower production cost than the valve device of the first embodiment. This 50 modified valve may have, as also in the case of the first embodiment, two open positions in lieu of the illustrated open and closed positions according to the fluid circuit control involved. Accordingly, in the broader patent sense the two illustrated positions will be referred to as 55 two operating positions without limitation as to their 60 respective specific purposes.

Operational summary

From the foregoing, it should be manifest that the 65 present valve mechanism simulates a "follow-up" control from the pedal 26 to the power apparatus SM as described for controlling an automotive friction clutch. As the pedal is depressed the clutch correspondingly engages with slight release of the pedal causing instant disengagement 70 of the clutch at any point along the full operating range of the pedal. After the clutch has become fully engaged, a disabling valve (not shown) may be included in the fluid control circuit FC to overrule further effectiveness of the present valve mechanism VM whereby the clutch 75 remains engaged irrespective of pedal manipulation until

a disengagement thereof is required as in bringing the vehicle to a stop or to facilitate change of speed ratio in the associated gearbox (not shown). The present invention contemplates supplemental control of the valve mechanism VM in response to shift-lever movements to enable stopping the vehicle by setting the shift-lever in neutral position with return of the lever to a gear-engaged position transferring the control of the valve mechanism to accelerator pedal operation to start the vehicle, and thereafter, the latter operation being disabled while the vehicle is underway until a change of gear ratio or stopping the vehicle is desired, such requiring the clutch members to be separated to interrupt torque transferal to the driving wheels of the vehicle as is understood.

It is also obvious from the two disclosures herein made, that the operation of the valve portrayed in Figures 1-4 inclusive may be more sensitized for a correspondingly shorter reciprocating stroke of the rod 24 than obtainable from the modified disclosure in Figure 5 since the former construction requires only such movement of the valve element 44, 45 as to effect face contact and separation thereof to produce the open and closed positions thereof; while in the latter construction, the valve land 150 width must be added to the overall actuating movement of the slideable valve element 144 in establishing the open and closed positions thereof.

Referring to the terminology used in the foregoing description and in the appended claims, the identifying expressions and/or terms employed are intended to convey meanings which include the range of reasonable equivalents in the patent sense. For example, the expressions, "movable assembly," "movable valve elements," "fixed assembly," "fixed valve element," are intended to include any structure providing for relative movement of fixed and movable elements whether such assembly provides for sliding or rotative movement of the elements, or a different type of movement serving the same purpose to open and close the assembly; the terms, "right," "left," "horizontal," "vertical," "angular," "depending," "upper," "lower," "bottom," "top," and other directional words or characters are intended to have only relative connotation for convenience in describing the structure as illustrated, and are not intended to be interpreted as establishing a definite operating position of the valve mechanism VM or requiring any particular orientation with respect to related structure of the present disclosure.

From the foregoing description augmented by an inspection of the drawings, it should be manifest that my invention provides a novel switch mechanism which is particularly adapted for incorporation in a servomotor control system and the like.

However, it is to be understood that the illustrated and described control system has been given by way of example only, and not in a limiting sense. In said exemplary system, the pivotal mounting S is obviously requisite. Such an arrangement may not be necessary should the actuating rod 24 be reciprocated along a constant plane.

Therefore, I do not desire to be restricted to the precise details illustrated and described, my invention contemplating any and all modifications and arrangements thereof, and such equivalents as may fall within the scope of the appended claims.

Having thus described my invention, I claim:

1. In a valve mechanism including a double-ended casing and a pair of relatively movable telescopically-related elements therein having cooperating seats normally engaged, a concentric seat on one of said elements; a fixed cooperating seat normally spaced from said concentric seat, a fluid chamber disposed between the pairs of cooperating seats aforesaid, a port establishing continuous communication between the chamber and exterior of the casing, another fluid chamber disposed between the one element and casing, a port establishing continuous communication between the exterior of the casing and the

last-mentioned chamber, a normally preloaded compression spring operably disposed between said pair of valve elements urging them into seated relationship with respect to each other, a passageway communicating with the first-mentioned cooperating seats, a port for establishing continuous communication between the exterior of the casing and said passageway, a longitudinal bore in the other element coaxially disposed with respect to said elements, a counterbore merging with said longitudinal bore, axially aligned circular openings through the ends of the valve casing, an actuator rod operably projecting from one end of the exterior of the casing through the openings and bores aforesaid to the exterior of the casing at the opposite end, a radially contractible split-type sleeve encircling said rod in continuous frictional engagement therewith and disposed in circular alignment with the surface of the counterbore, an internal annular shoulder provided at the point of emergence between the bores aforesaid to engage one end of the split sleeve, an internal annular shoulder defining the outer terminus of the counterbore adjacent the other end of the split sleeve to thus prevent axial displacement of the split sleeve with respect to the other element, an enlarged diameter portion on the rod defining an annular shoulder therewith to effect limited retracting movement of said rod and valve elements toward their respective fully retracted positions wherein the pair of elements is in seated relation and the one element spaced from its fixed seat, and means for actuating said actuator rod.

2. The valve mechanism according to claim 1 in which the counterbore is press-fitted with a cylindrical sleeve terminating at its outer end with an internal annular shoulder to provide an internal annular space with the opposite end of the counterbore confronting said annular shoulder, said annular space receiving said contractible sleeve for radial movement only relatively thereto between said spaced annular shoulders.

3. The valve mechanism according to claim 2 including a pair of longitudinally spaced grooves provided in the surface of the enlarged diameter of the rod for selective engagement by a yieldable detent carried by the valve casing to releasably establish the movable valve elements in their respective operating positions corresponding to open and closed condition.

4. The valve mechanism according to claim 3 including a longitudinal bore merging with a counterbore through the fixed valve seat in coaxial disposition with respect to the axis thereof for slidably supporting a portion of the other valve element; an internal annular shoulder at the point of emergence between said last-mentioned longitudinal bore and counterbore, for engagement by the confronting end of the other valve element when moved; an annular hollow reduced diameter projection disposed on the opposite end of the valve casing in coaxial disposition therewith; an inturned annular flange defining the terminus of said projection and marginal edge of the opening through which the actuator rod projects for engagement by the opposite end of the other valve element when fully released whereby the limits of the reciprocatory movement of the pair of valve elements is established.

5. The valve mechanism according to claim 4 including a laterally projecting pin journaled in a suitable fixed aperture for mounting the mechanism in operation position.

6. In a valve mechanism comprising: a hollow valve body; a valve seat fixed within said body; a pair of telescopically-related valve elements movable relatively with respect to each other and together; inner and outer concentric valve seats carried on one of said valve elements, said outer seat cooperating with said fixed seat; a valve seat carried by the other valve element cooperating with the inner seat aforesaid; a pair of fluid chambers disposed on opposite sides of the one valve element with one of said chambers disposed between the valve elements; a

port establishing continuous communication between one of said chambers and the exterior of the valve body; another port establishing continuous communication between the other chamber and the exterior of the valve body; a third fluid chamber disposed between the one valve element and one end of the valve body; a port establishing continuous communication between the exterior of the valve body and said third chamber; a passageway establishing continuous communication between the third chamber and the chamber between said valve elements; a normally preloaded compression spring carried by the other element for biasing the one element into seated relation with the other element; another normally preloaded compression spring for biasing both valve elements into normal released position wherein the outer concentric seat is spaced from its fixed seat placing the pair of chambers in communication with each other, and the cooperating seats between the valve elements in seated relation to isolate the pair of chambers from the third chamber; reciprocative means coaxially disposed with respect to said valve elements for moving them; and a friction element incorporated in said reciprocative means and operable in response to minute reciprocations of the latter at any selected position intermediate the limits of the full operating stroke thereof for moving said valve elements to establish fluid communication between the three mentioned ports.

7. In a valve mechanism for controlling a fluid circuit including a valve body having a fixed annular seat therein; a pair of telescopically-related valve elements movable relatively with respect to each other and together; inner and outer concentric valve seats carried on opposite sides of one of said valve elements, said outer seat cooperating with said fixed seat; an annular concentric valve seat carried by the other valve element cooperating with the inner confronting concentric seat on the one valve element; means for normally biasing said pair of valve elements into seated relationship with respect to each other and the one valve element spaced from the fixed seat; a fluid chamber disposed between the one valve element and fixed seat in continuous communication with a passageway leading to the exterior of the casing; a second fluid chamber disposed between the pair of valve elements and confronting valve seats thereof in continuous communication with a passageway leading to the exterior of the casing; a third fluid chamber disposed between the pair of valve elements and one end of the casing in continuous communication with a passageway leading to the exterior of the casing; reciprocatory means for moving said pair of valve elements out of engagement with respect to each other to establish their confronting seats in spaced relationship and the outer seat into engagement with the fixed seat to isolate the first-mentioned chamber from the third chamber and to connect the latter chamber with the second chamber; and a friction element operable in response to minute reciprocations of the reciprocatory means at any selected position intermediate the limits of the full operating stroke thereof for alternately moving said pair of valve elements into and out of engagement with respect to the fixed seat and the confronting seats thereof to open and close said fluid circuit respectively.

8. In a valve mechanism for controlling an associated fluid circuit including a hollow valve body having longitudinally spaced end walls and a pair of ports leading from the hollow of the valve body in continuous com-

munication with the exterior of the valve body; a reciprocatable valve assembly movable within the hollow of the valve body relatively to said pair of ports for controlling the latter; a longitudinal bore through the valve assembly having an intermediate annular space of larger diameter defining an internal annular shoulder at each end thereof; a pair of axially aligned circular openings provided in the end walls of the valve body and concentrically disposed with respect to said longitudinal bore; a reciprocative element projecting through the wall openings of the valve body and said longitudinal bore in the valve assembly; a contractile longitudinally split friction sleeve confined between said pair of internal annular shoulders for axial movement with the valve assembly and encircling said reciprocative element in continuous frictional engagement therewith; means for continuously biasing the valve assembly toward connecting said ports; and means for imparting minute reciprocations to the reciprocative element at any selected position intermediate the limits of the full operating stroke thereof for alternately moving the valve assembly to connect and disconnect said pair of ports resulting in the associated fluid circuit being opened and closed respectively.

9. The valve mechanism according to claim 8 including an internal annular channel in the surface of the valve body hollow spaced from the valve assembly in normal port connecting disposition; a split resilient retainer ring engaging said channel for engagement by the confronting end of the valve assembly when moved by said last-mentioned means; and an inturned annular flange provided on the marginal portion of the opening through the opposite end wall of the valve body for engagement by the opposite end of the valve assembly when in normal port connecting disposition whereby the reciprocative movement of the valve assembly is limited.

10. The valve mechanism according to claim 9 including a plurality of ports through the wall of said inturned flange for maintaining communication between a portion of the interior of the valve body and the exterior thereof; and a venting cap mounted on said opposite end wall of the valve body and spaced from said plurality of ports for preventing foreign particles from entering said interior of the valve body.

11. The valve mechanism according to claim 10 in which the free end of the reciprocative element is provided with a larger diameter to produce an external annular shoulder with the normal smaller diameter thereof, said larger diameter projecting through the opening in the end wall of the valve body correspondingly enlarged to accommodate the same, and said shoulder normally engaging the confronting end of the valve assembly to releasably maintain the latter in port connecting disposition wherein the opposite end of the valve assembly is engaged with the inturned flange of the opposite end wall of the valve body.

12. The valve mechanism according to claim 11 including a laterally projecting pin journaled in a suitable fixed aperture for mounting the mechanism in operating position.
